UNITED STATES PATENT OFFICE

CECIL H. LAWRENCE, OF ATTLEBORO, MASSACHUSETTS, ASSIGNOR TO EVANS CASE COMPANY, OF NORTH ATTLEBORO, MASSACHUSETTS, A CORPORATION OF MASSACHUSETTS

DESIGN FOR A BAG ORNAMENT

Application filed July 1, 1929. Serial No. 31,905. Term of patent 3½ years.

To all whom it may concern:

Be it known that I, CECIL H. LAWRENCE, a citizen of the United States, and a resident of Attleboro, in the county of Bristol and State of Massachusetts, have invented a new, original, and ornamental Design for Bag Ornaments, of which the following is a specification, reference being had to the accompanying drawing, forming part thereof.

The figure is a front elevation of a bag ornament, showing my new design.

The bag ornament is substantially flat.

I claim:

The ornamental design for a bag ornament as shown and described.

In testimony whereof, I have signed my name to this specification this 18th day of June, 1929.

CECIL H. LAWRENCE.
